[57] CLAIM

The ornamental design for a hand held rotary cutting tool, as shown and described.

DESCRIPTION

FIG. 1 is a perspective view of the hand held rotary cutting tool;

FIG. 2 is a top view of the hand held rotary cutting tool;

FIG. 3 is a side view of the hand held rotary cutting tool;

FIG. 4 is the other side view of the hand held rotary cutting tool;

FIG. 5 is a bottom view of the hand held rotary cutting tool;

FIG. 6 is a rear view of the hand held rotary cutting tool; and,

FIG. 7 is a front view of the hand held rotary cutting tool. The broken line showing of a power cord and keeper is for illustrative purposes only and forms no part of the claimed design.
